Lullabye Catalog, p. 38, #2220 crib at top left.

Primary Examiner—Janice E. Seeger

Attorney, Agent, or Firm—David W. Carstens; Strasburger & Price L.L.P.

[57] CLAIM

The ornamental design for a crib, as shown.

DESCRIPTION

FIG. 1 is a perspective view of a crib embodying our design; FIG. 2 is an end view of the crib; FIG. 3 is a side view of the crib; FIG. 4 is a top view of the crib; and, FIG. 5 is a bottom view of the crib.

"The opposite end and side not shown are identical to those shown in FIGS. 2 and 3 respectively. The interior surface of both end panels and side rails is plain and unornamented."
